CLAIM

The ornamental design for a display screen or portion thereof with graphical user interface, as shown and described.

DESCRIPTION

The patent file contains at least one drawing executed in color. Copies of this patent with a color drawing will be provided by the Office upon request and payment of the necessary fee.

FIG. 1 is a front view of a first embodiment of display screen or portion thereof with graphical user interface embodying the new design; and,

FIG. 2 is a front view of a second embodiment thereof. The broken lines showing a display screen forms no part of the claimed design.

**1 Claim, 2 Drawing Sheets
